UNITED STATES PATENT OFFICE.

LEWIS D. NELSON, OF COLDWATER, MICHIGAN.

SWITCH.

Application filed October 26, 1922. Serial No. 597,026.

To all whom it may concern:

Be it known that I, LEWIS D. NELSON, a citizen of the United States, residing at Coldwater, county of Branch, State of Michigan, have invented certain new and useful Improvements in Switches, of which the following is a specification.

This invention relates to improvements in switches. My improved switch is especially 10 designed by me for controlling the lamps of automobiles having full and dimmer circuits and is also designed to be mounted upon a steering wheel for manipulation by the operator of the vehicle grasping the steering 15 wheel rim.

The main object of this invention is to provide an improved switch of this class which is simple and economical in structure and very strong and durable.

Objects pertaining to details and economies of construction and operation will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing forming a part of this application, in which:

Fig. I is a plan view of the steering wheel of an automobile with my improved switch 35 mounted thereon, portions of the wheel being broken away for convenience in illustration.

Fig. II is an enlarged detail view, partially in section, on a line corresponding to line 2—2 of Figs. III and IV.

Fig. III is a horizontal section on a line corresponding to line 3—3 of Fig. II, the position of the switch block relative to the parts shown in this figure being indicated by 45 dotted lines.

Fig. IV is a detail view, partially in section, on a line corresponding to line 4—4 of Fig. II.

Referring to the drawing, 1 represents the 50 rim of a steering wheel of conventional type and 2 the spokes thereof. My improved switch comprises a cupped top casing member 3 and a cupped bottom casing member 4, the casing members being disposed edge to edge and secured by rivets 5.

The bottom casing member 4 is shouldered

at 6 to support the insulating disk or plate 7 and provides a chamber 8 below the plate for the electrical connections 9, the bottom of the bottom casing member having a hole 10 for the cable 11. The fixed plug-like contact members 12 are disposed through the plate 7 at one side thereof. Above the plate and pivotally supported thereon by the post 13 is a switch block 14 having a recess 15 on its under side. The spring contact 16 is mounted in this recess by means of the screw 17 to coact with the contacts 12 which have curved recesses at their upper ends to receive the spherically curved end 18 of the spring contact 16. A recess 19 is provided by the contacts 12, the contacts 16 engaging with this recess for holding the switch in neutral position.

The plate 7 has a bore 20 therein communicating with the chamber 8 to accommodate the electrical connections for the contact 16. The top casing member has a slot 21 at one side thereof through which the handle 22 of the switch block projects, the handle being of such length that it may be manipulated by the operator grasping the rim of the wheel when the casing is secured upon a spoke of the wheel as by means of the clamp 23 which is secured in position by means of the screws 24.

My improved switch is well adapted for use in controlling the headlights of automobiles, the parts are simple and economical to 90 produce and assemble, and the structure is very strong and durable.

Having thus described my invention what I claim as new and desire to secure by Letters Patent is:

1. In a switch, the combination of a casing comprising cupped top and bottom casing members disposed edge to edge, the top casing member having a slot at one side thereof and being provided with a clamp for securing the casing to the spoke of a steering wheel, the bottom member having an annular shoulder, a pivot post disposed through said casing members, an insulating plate disposed upon said shoulder in said bottom casing member providing a chamber below the plate for the electrical connections, spaced contact plugs disposed through said insulating plate, a switch block of insulating material pivoted on said post to rest on said plate, said block being recessed on its under side, a spring contact secured

- in said recess to coact with said contact plugs, said spring contact constituting a detent for holding said switch block in its adjusted positions, said plate having a bore open to said chamber accommodating the electrical connections for said spring contact, and a handle for said switch block disposed through said casing slot in position to be manipulated by the operator grasping 10 the rim of the steering wheel to which the casing is attached.
2. In a switch, the combination of a casing comprising cupped top and bottom casing members disposed edge to edge, the top 15 casing member having a slot at one side thereof, the bottom member having an annular shoulder, a pivot post disposed through said casing members, an insulating plate disposed upon said shoulder in said 20 bottom casing member providing a chamber below the plate for the electrical connections, spaced contact plugs disposed through said insulating plate, a switch block of insulating material pivoted on said post to 25 rest on said plate, said block being recessed on its under side, a spring contact secured in said recess to coact with said contact plugs, said spring contact constituting a

detent for holding said switch block in its adjusted positions, said plate having a bore 30 open to said chamber accommodating the electrical connections for said spring contact, and a handle for said switch block disposed through said casing slot.

3. In a switch, the combination of a casing 35 comprising cupped top and bottom casing members disposed edge to edge, the top casing member having a slot at one side thereof and being provided with a clamp for securing the casing to the spoke of a steering wheel, a pivot post carried by said casing members, an insulating plate disposed in said bottom casing member, spaced contact 40 plugs disposed through said insulating plate, a switch block of insulating material pivoted 45 on said post to rest on said plate, said block being recessed on its under side, a contact secured in said recess to coact with said contact plugs, and a handle for said switch block disposed through said casing slot in 50 position to be manipulated by the operator grasping the rim of the steering wheel to which the casing is attached.

In witness whereof, I have hereunto set my hand and seal.

LEWIS D. NELSON. [L.S.]
